UNITED STATES PATENT OFFICE.

CHARLES R. GREUTER, OF SPRINGFIELD, MASSACHUSETTS, ASSIGNOR TO
JAMES C. KEOUGH, OF HOLYOKE, MASSACHUSETTS.

MECHANICAL STOKER.

SPECIFICATION forming part of Letters Patent No. 595,945, dated December 21, 1897.

Application filed June 25, 1896. Serial No. 596,897. (No model.)

To all whom it may concern:

Be it known that I, CHARLES R. GREUTER, a citizen of the United States, residing at Springfield, in the county of Hampden and 5 State of Massachusetts, have invented certain new and useful Improvements in Mechanical Stokers, of which the following is a specification.

My invention pertains to mechanical stokers for furnaces; and it consists in various 10 novel features, combinations, and details hereinafter set forth.

The invention is susceptible of application to furnaces generally, but is peculiarly 15 suited to boiler-furnaces, since in its preferred embodiment it comprises as a part of the complete structure or combination a water-motor taking its supply from the boiler and under the pressure therein. This, however, 20 is not an essential feature, though deemed a very desirable and advantageous plan.

In the accompanying drawings, Figure 1 is a perspective view of a furnace-front with my improved stoking apparatus applied; 25 Fig. 2, a perspective view of the fuel and ash grates, the furnace-front, and motor, looking from the inner or rear side of the front plate; Fig. 3, a longitudinal vertical section of the stoking apparatus, grates, and fire-chamber, 30 showing the bridge-wall and lower front portion of the boiler; Fig. 4, a vertical transverse section on the line $x x$ of Fig. 3; Fig. 5, a sectional view of the clutch for connecting and disconnecting the stoking devices with and 35 from the motor.

The purpose of my invention is to produce a simple and efficient apparatus for stoking or charging furnaces generally, whereby most of the labor incident to manual stoking shall 40 be rendered unnecessary and the uniformity of the stoking and firing so increased as greatly to economize fuel.

The term "stoking" is here employed in its more comprehensive sense, implying not 45 merely the feeding or introduction of fuel, but also the proper distribution thereof and the removal of ashes, &c., or, in other words, the "trimming" of the fire.

It is of course desirable that the apparatus 50 shall be capable of manual actuation in order

that the fire may be properly started and maintained prior to development of pressure sufficient to actuate the motor or in the event of use where fluid-pressure is not available. So, too, it is advisable to provide for the feeding of fuel without shaking the grate or agitating the fire or to vary the relation of these two operations as to degree. A forced draft is sometimes advantageous, and if provided it should be subject to perfect regulation and 60 control not only as to strength, but also as to the point or points of application to or passage through the fuel. These and other matters are carefully provided for in the construction illustrated in the drawings and 65 which will now be described.

A indicates a fire-box or combustion-chamber, here represented as that of a boiler-furnace; B, the bridge-wall; C, a boiler or steam-generator; and D, a furnace-front, to which 70 are applied the fuel-feeding devices.

The boiler may be present or not, as found expedient in any given case, but will be carried into this description for better explanation of the complete scheme of operation. 75

The furnace-front D, consisting, essentially, of a cast-iron plate, is formed with a hopper E, extending from the middle toward each side of the front and of a width approximately half that of said front ordinarily, 80 though its dimensions may vary as found best.

The hopper E is designed to receive and hold a considerable supply of fuel, which falling to the bottom of the hopper rests upon a 85 flat or horizontal bed a, from which it is forced through an opening b in the furnace-front D by a reciprocating slide or pusher F, Figs. 1 and 3.

Just within the back of the front plate D 90 is a hollow casting G, bolted to the furnace-front and serving as a girder or bracket to support and carry the masonry of the front immediately below the front end of the boiler C. This casting G is formed with a throat c, 95 the mouth or lower and outer opening of which registers with opening b of the front plate D. The throat c has an upward inclination from the opening b rearward and also widens or increases in vertical measurement 100.

rearwardly with a view to preventing the fuel from being clogged or retarded in its passage therethrough.

It has been the general practice heretofore either to make the floor or lower side of the feeding throat or passage horizontal or to give it a downward inclination from the furnace-front inward toward the fire-box; but this I find undesirable, for the reason that the fuel is thereby caused to fall away from the feed-opening and to leave an insufficient quantity at the head of the grate to insure the best working conditions. As mentioned, I give the throat or passage an upward inclination, making this sufficient to cause the fuel to form a fairly compact mass. This not only enables me to judge accurately and at all times the quantity of fuel that will be introduced in a given time, but it precludes any considerable ingress of air through the throat or feed-opening, and thus prevents the undue deadening of the fire, on the one hand, or the premature ignition and combustion of the fuel, on the other hand. This feature of construction I find of very considerable importance, materially improving the action of the apparatus and enhancing the economy of its use.

The pusher or feeding-slide F is merely a metallic block or casting of a length equal to that of the interior of the hopper and of throat c and of a height at its inner edge or face somewhat less than that of opening b. At its front or outer edge it is formed with ears d, which are connected by bolts to arms e, projecting radially from a sleeve H, encircling a shaft I, which shaft receives an oscillating motion from a motor J through the medium of an arm f, secured upon shaft I, and a pitman g², connected with the piston of the motor.

Sleeve H is loose upon shaft I, but may be connected therewith through the medium of devices shown in Figs. 1, 3, and 5, which will now be explained.

K indicates a rocking head or casting loosely encircling the shaft I and projecting above and below the same in the form shown in Figs. 1, 3, and 5. The lower extension of this head or rocker is in the form of two separated but parallel arms g, between which is hung a block h, carrying a sleeve i to receive a pitman or connecting rod L, through which motion is transmitted to the grate-bars, as hereinafter explained.

The upper portion of the head or rocker K has at its rear side a laterally-projecting and shouldered rib j, adapted to engage one of the arms e of sleeve H and to carry said arm and sleeve forward with it when head or rocker K is rocked in that direction. Projecting forward from the upper portion of the head or rocker K is an extension k, the outer portion of which is offset so as to stand opposite to or in line with the outer face of the same arm e, behind which stands the shoulder or rib j. The extension k is bored

or drilled and tapped to receive a heavy screw l, the inner end of which may be carried directly against the arm e or as near thereto as desired, its adjustment determining whether or not there shall be any play or lost motion of the head K relatively to sleeve H, and if so how much. The outer end of the screw-stem is furnished with a hand-lever, wheel, or other contrivance by which to turn it.

Since the grate receives motion through connection with the lower arms g of head or rocker K and the feeding-slide or pusher F receives motion through connection with the arms e of sleeve H, it will be apparent that the relative extent of their movements may be determined by the adjustment of screw l.

The head or casting K is further formed with a socketed neck or boss m to receive a hand-lever by which to rock the head and actuate the feed-slide and grate, as indicated in Fig. 3. When the apparatus is to be thus manually actuated, the rocking head K is left free and loose upon shaft I, except for its connection therewith through the shouldered rib j and screw-stem l, but as it is desirable ordinarily to actuate the whole through power applied to the shaft I provision is made for locking the head or rocker to the shaft. For this purpose there is keyed or otherwise made fast upon the shaft I beside head K a sleeve M, provided with a tubular shell m', in which is arranged a sliding bolt n, adapted to be protruded from the shell and to be entered into a seat or socket o in the head or rocker K, as indicated in Figs. 1 and 5. The bolt n is in all essential particulars like an ordinary cylindrical door-bolt, having an operating-handpiece p extending through a slot q, formed with seats or depressions to receive the handpiece p and to retain the bolt at either limit of its travel.

In order that the movement of the grate-bars or grate may be made relatively less than that of the feeding-slide F when desired, the pitman or connecting rod L is shouldered in rear of sleeve i, as shown in Fig. 3, and a nut or follower q' is screwed upon the rod L at its outer end or in front of sleeve i. By properly adjusting this nut or follower and screw-stem l any desired relative play may be secured.

It is important in any apparatus of this sort that all parts be accessible and susceptible of manual regulation and control. Thus it is desirable that the attendant shall be able at any time to pass his fire-tools into throat c or through the same and into the space beyond; and it is likewise advisable to maintain a fairly close sealing of the opening at the front of the hopper, through which the feeding-slide or follower passes. To meet both requirements, the opening through the front of the hopper E is made considerably higher than the slide or follower, except near each end, and the opening is normally closed by a vertical gate N, the lower edge of which rests upon slide or follower F and the ends of which are or may be held in place by overlapping

plates secured to or ribs cast upon the hopper. The gate is free to rise and fall and is advisably furnished with handles by which to lift it from position when it is desired to open the space above the pusher or follower F.

- For the purpose of supplementing the weight of the gate N and thus more certainly maintaining a close joint between its lower edge and the follower I provide one or more levers O, each having an upturned end to engage beneath a lug or ear q^2 , formed upon or secured to the front of the hopper, and each furnished with a pendulous link r, having at its lower end a T-head to rest in or upon ears or lugs s, formed upon or attached to the gate, all as plainly shown in Figs. 1 and 3. The levers O may be weighted to give any desired pressure of the gate upon the slide or follower.
- Extending inward from the furnace-front D is a frame composed, essentially, of two side plates P P, two cross-bars Q and R, and a box-like cross connection S, the latter serving as an air space or chamber and being covered by a ribbed and perforate plate T, the outer edge of which joins the inner edge of the bottom or floor of feeding-throat c, as shown in Figs. 2 and 3.

The side plates P P are bolted to the furnace-front D, and the connecting members Q, R, and S are bolted to the side plates, as indicated in Figs. 2 and 3. The lower ends of the side plates rest upon the floor of the ash-pit, and the cross-bar R extends beneath a projection of the bridge-wall, so that all parts are retained firmly in place, yet may be readily withdrawn for renewal or repair after being properly unbolted.

As seen in Figs. 2 and 3, cross-bar Q is formed with a horizontal flange t along its forward or outer side and with horizontally-projecting fingers u along its rear face, the latter producing a comb-like ledge, as shown. U indicates the fire-grate, upon which the fuel is burned, and V the clinker or cinder grate, which receives the spent or partially-spent fuel, clinker, &c., and discharges them into the ash-pit beneath when necessary.

The grate U may be of any approved type, but is preferably composed of parallel bars or members w and x, the former bolted to the cross member S or other suitable support and the latter adapted to move relatively to the former to effect proper agitation of the fire and discharge of ashes.

The lower ends of both sets of bars w and x are slotted to fit over the projecting flange t of cross-bar Q, the slots being of such length as to provide for any expansion that may occur and the bearing being sufficient to preclude withdrawal from the flange t under the greatest contraction possible.

The grate-bars are quite heavy, and this weight, augmented by that of the fuel, necessitates the expenditure of considerable force to move the grate-bars x. To make the movement as free as practicable, each bar is formed

with an elongated horizontal opening y in its lower end, as seen in Fig. 3, and cylindrical rods or rollers z are passed through the openings of a series of the bars and serve as rolling bearings for the movable bars x, the rolls moving upon the fixed bars and the movable bars traveling upon the rolls. The bars x should have no direct or actual bearing upon the flange or rib of cross-bar Q under ordinary circumstances, but in the event of the rolls working out of any of the movable bars they would be kept in position by said flange.

To permit the ready insertion of the rollers z where the masonry is completed prior to setting the grate and to provide also for removal at any time, the rollers z are preferably made of a length equal to half the width of the grate approximately, and when about half the bars are set in place the two rollers are passed side by side into the openings y of said bars. The other bars are then set up, and then one of the rollers is moved endwise to its place in the second half, or, in other words, the rollers are placed end to end and in alinement, each thus tending to retain the other in place, since they move equally and simultaneously and remain in alinement.

For the purpose of reciprocating or moving the bars x there is provided a rock-shaft W, carrying a series of arms or projections which serve both to support and to impart motion to the grate-bars.

The construction of the rock-shaft may vary, but I prefer that illustrated in Figs. 1 and 4, where the shaft is represented as of square form in cross-section, but with its ends turned cylindrical to form journals, which are preferably carried in roller-bearings, as illustrated in Fig. 4.

Each bar x is formed with an open-sided circular seat a' to receive the boss or head b' of a block c', made in the form of a sleeve or collar to closely encircle the shaft W. These blocks c' may be cast or forged, as desired, and may be shrunk, keyed, or otherwise secured upon the rock-shaft V or merely slipped to place thereon, passing between the fixed bars w and being thus prevented from shifting laterally to any material extent.

One of the blocks or sleeves c' is formed with depending arms d', Figs. 3 and 4, for connection with the rod L, through which motion is imparted to the grate-bars x.

The construction shown and described is simple, strong, and efficient, the bars x receiving a longitudinal movement and also a rising-and-falling movement at their upper ends, whereby the ashes are effectively shaken out and the coal is caused to work down over the fire-grate surface, the cinders finally falling upon the lower grate V.

The grate-bars w and x are represented as of stepped form, with horizontal or slightly-concaved plates or portions corresponding to the treads of steps and with openings beneath the plates through which air may enter. This construction is found to give excellent

results and to insure very perfect combustion, but may be departed from, if desired.

The grate V is or may be of any usual grate form, but is preferably made in two sections each extending half-way from one side plate P to the other, as seen in Fig. 2. Each section is formed with journals or gudgeons e' near its rear side, which rest in suitable seats or bearings in the grate-frame. This construction is for the purpose of permitting the front of each section to be dropped from its normal position to dump the cinders, clinkers, &c., accumulated thereon, or to be quickly raised and lowered a short distance to break up and dislodge any clinker or slag that may form along the comb-like ledge u.

For the double purpose of maintaining the clinker-grate sections normally in horizontal plane and of moving them vertically when required each section is provided near its free or moving edge with a supporting brace or frame X of the form shown in Figs. 2, 3, and 4. These braces are each in the form of a triangular frame, one side or member of which extends beneath and is hinged or jointed to the grate-section, while at its lower angle there is a lateral projecting stud or axle f', preferably furnished with a roller g', which rests and travels upon a supporting flange or rib h', formed upon or bolted to the proximate side plate P and of curved form at its forward end, as shown, the curve being of relatively shorter radius than the supporting frame X.

Y indicates an actuating bar, one end of which is hung upon the bolt or axle f' and the other end of which, protruding through and beyond front plate D, is fashioned into a handhold, as shown in Figs. 1 and 3. There is a bar Y for each brace or support X, and each bar is provided with a notch in its lower edge to engage with the lower wall of the opening in the front plate D, through which it passes, said notch being located in position to lock the bar at that point at which it will hold the brace in a vertical position, and consequently retain the grate-section in horizontal plane.

The curvature of the forward end of the rib or flange h' is such that when the bar Y is drawn forward from its normal position the brace X, and consequently the forward side of grate-section V, will be elevated above its normal plane; but as the angle of the brace to the grate-section changes from a right angle to an obtuse one the force required to move the brace forward decreases as the distance moved increases.

I have above referred to the box-like connecting member S and its cover T, designed to serve the double function of connecting the side plates P P' and containing and distributing air for aiding combustion. Air is introduced into the box or chamber S by a trunk Z, Fig. 3, and may be forced into and through the same by any convenient means if natural draft be inadequate. In the draw-

ings I have indicated by dotted lines an annular blower of common form, located in the induction end of the trunk, but any other type of air-forcing device may be employed, or in some cases none need be used.

From the box S the air escapes through broad flat mouths or nozzles i', formed in the top or cover T of said box, as shown in Figs. 2, 3, and 4, these mouths or nozzles being separated by channels, grooves, or depressions, which become filled with ashes in a short time and prevent the plate or top from burning out. For a like purpose the horizontal portions of side plates P P' are similarly grooved or channeled.

The lower side of box S is provided with a sliding bottom or damper j', having a handle k' projecting beyond the furnace front. By opening this damper more or less air may be permitted to pass in any desired quantity to and through the grate-bars under whatever pressure is maintained within the box. By opening the ash-pit doors more or less a natural draft may be caused through said grate.

The cover or top T continues the upward inclination of the bottom of throat c.

At the sides or ends of the hopper E there are openings through the front plate D, closed by suitable doors, by opening or closing which the fire may be regulated with nicety or access may be had to the fire-box for any purpose.

The construction of the motor may vary as desired, though there is a material advantage in employing a hydraulic motor and connecting its supply-pipe with the boiler below the low-water level, so that the motor may at all times receive water at boiler-pressure, but not receive steam. The water-motor gives abundant power, operates somewhat slowly or gradually, and causes but little loss of heat, the water being discharged into the feed-water well or tank and pumped back to the boiler with practically no loss other than the power required to restore the water to the boiler.

The apparatus constructed as above set forth has been found extremely satisfactory in use, showing great economy in fuel consumption relatively to evaporation, and this because of the even distribution of fuel, the clean grate, and the proper supply of air to the whole body of fuel.

The clinkers, slag, slate, &c., which ordinarily deaden a fire are in a short time worked down over the fire-grate and delivered to the clinker-grate, whence they are delivered by lowering the front of the clinker-grate, any clinker or slag forming at the foot of the fire-grate being broken and loosened by moving the rods Y back and forth, and thus throwing the clinker-grates up and down at their forward edges.

Having thus described my invention, what I claim is—

1. In a stoking apparatus for furnaces, the combination of a downwardly-inclined grate;

- a fixed bed or fuel-support at the upper end of the grate; a feed-hopper; an upwardly-inclined feeding throat or passage, the lower wall or floor of which extends in a direct line
- 5 and at a slight upward inclination from the bottom of the feed-hopper to the fixed fuel bed or support; and a reciprocating slide working across the hopper and serving to force material therefrom through the feed-ing-passage and to deliver it upon the fixed fuel bed or support, substantially as set forth.
2. In combination with the fire box or chamber of a furnace; a fuel-hopper; a reciprocating slide or pusher movable across said hopper; an opening extending across the hopper above the slide; and a gravitating gate bearing upon the slide at the forward or outer side of the hopper, and serving the double purpose of a closure for the opening and a scraper 20 for the slide.
3. In combination with hopper E having lugs *q*; gate N provided with lugs *s*; and levers O provided with links *r*, all constructed and arranged substantially as described and shown.
- 25 4. In combination with fuel-hopper E and slide or pusher F, a delivery-trunk *c* extending upward therefrom at a slight inclination and of regularly-increasing vertical measure-30 ment; and a fuel-bed or supporting-plate T at the rear end of the trunk *c*; all substan-tially as described and shown.
- 35 5. In combination with a feed-hopper, a de-livery-slide or pusher; a shaft; a sleeve en-circling said shaft and having a radial arm connected with the slide or pusher; a rock-ing head carried by the shaft, movable rela-tively to the sleeve and provided with a shoul-30 der to engage the arm of said sleeve; and a screw also carried by the rocking head and adapted to bear upon the arm of the sleeve at a point opposite that at which the shoulder bears; whereby the rocking head is adapted to impart movement to the sleeve, but with 45 lost motion determined by the adjustment of the screw.
- 40 6. In combination with shaft I, sleeve H en-circling said shaft provided with arms *e*, *e*; slide or pusher F connected with said arms; hopper E; rocker K provided with shouldered rib *j* and screw *l*; sleeve M provided with bolt *n*; arm *f* secured to shaft I; and motor J con-nected with arm *f*.
- 45 7. In combination with a feed-hopper and a feeding-slide or pusher; a rocking sleeve or shaft connected with and serving to reciprocate said slide; a rocking head adapted to receive the power required for oscillating the sleeve or shaft; means for connecting and disconnecting the rocking head with a source of power and an adjustable connection be-tween the rocking head and sleeve or shaft, whereby the extent of movement of the sleeve or shaft may be varied while that of the head 50 remains constant.
- 55 8. In combination with hopper E; slide F; shaft I; sleeve H provided with arms *e* for moving the slide F; rocking head K; and means substantially such as described and shown for connecting the sleeve and the rock-ing head.
- 70 9. In combination with a suitable frame, the grate composed of alternate fixed and movable bars *w* and *x*; rock-shaft W pro-vided with removable sleeves *c* having bosses *b*; and means for oscillating said shaft.
10. In combination with grate-bars *w* and *x* provided with slots *y*; rollers *z* passing through said slots; and rock-shaft W, hav-ing bosses *b* seated in recesses in the bars *x*.
- 80 11. In combination with a series of alter-nate fixed and movable grate-bars, each pro-vided with a slot *y*; two rollers *z*, passing through said slots and placed in axial aline-ment, substantially as and for the purpose 85 set forth.
12. In a furnace, the combination of an air-box located at the front of the fire-grate and provided with a series of upwardly-projecting mouths or nozzles for delivery of air; and means for producing a blast or forced draft through said nozzles.
13. In a furnace, an air-box located at the front of the fire-grate, and provided at its top with a series of upwardly-projecting mouths 95 or nozzles for delivery of air.
14. In combination with an inclined fire-grate; an air-box at the front thereof pro-vided with openings in its top for escape of air above the grate, and with an opening in 100 its bottom provided with a slide or damper to permit and control delivery of air beneath the grate.
15. In combination with a grate-frame hav-ing a toothed bar; and with an inclined grate 105 carried by said frame; a clinker-grate located at the lower side of the inclined grate; and means substantially as described for moving the edge of the clinker-grate past the toothed bar, for the purpose set forth.
- 110 16. In combination with a grate-frame pro-vided with a rib *h*', having an upwardly-turned forward end; a grate V pivoted at a point distant from its front edge; and a sup-115 porting-brace X having a roller *g*' arranged to traverse the upwardly-turned portion of the rib and thereby to elevate the front of the grate above its normal plane.
17. In combination with a grate-frame hav-ing toothed bar Q and flange or rib *h*' curved 120 as described; swinging grate V; brace X; roller *g*' carried by said brace and arranged to traverse the curved portion of rib *h*'; and bar Y for moving the brace; whereby the free edge of grate V is caused to move upward 125 past the teeth of bar Q and thereby to break and dislodge clinkers there located.
- In witness whereof I hereunto set my hand in the presence of two witnesses.
- CHARLES R. GREUTER.
